CLAIM

The ornamental design for a conduit adapter for electrical boxes, as shown and described.

DESCRIPTION

FIG. 1 is a top plan view of the conduit adapter for electrical boxes of the present invention, the bottom plan view being substantially identical thereof;

FIG. 2 is a right side elevational view of the conduit adapter for electrical boxes of FIG. 1, the left side elevational view being a mirror image thereof;

FIG. 3 is a front elevational view of the conduit adapter for electrical boxes of FIG. 1; and,

FIG. 4 is a back elevational view of the conduit adapter for electrical boxes of FIG. 1.
